UNITED STATES PATENT OFFICE.

EDWARD SCHAEFER AND OSCAR J. HOLMES, OF ST. LOUIS, MISSOURI, ASSIGNEES TO
O'NOFREZ' O FIRE EXTINGUISHER MANUFACTURING COMPANY, OF ST. LOUIS, MISSOURI, A CORPORATION OF MISSOURI.

FIRE-EXTINGUISHER.

1,259,783.

Specification of Letters Patent. Patented Mar. 19, 1918.

Application filed December 16, 1913. Serial No. 806,995.

To all whom it may concern:

Be it known that we, EDWARD SCHAEFER and OSCAR J. HOLMES, citizens of the United States, and residents of St. Louis Missouri have invented certain new and useful Improvements in Fire-Extinguishers, of which the following is a specification containing a full, clear, and exact description, reference being had to the accompanying drawings, forming a part hereof.

Our invention relates to improvements in fire extinguishers and is especially directed toward the class of extinguishers known as portable, chemical fire extinguishers. The primary object of our invention is to construct a container for a non-freezable compound having fire extinguishing qualities, and to place in the container a duplex water tight receptacle arranged to hold sealed within itself two distinct elements which when united will form an expelling charge for the fire extinguishing compound.

A further and more specific object of our invention is to provide a novel means common to both for simultaneously freeing the expelling substance and fire extinguishing compound.

With the above purposes in view our invention consists in certain novel features of construction and arrangement of parts as will be hereinafter more fully described, pointed out in the claims and illustrated by the accompanying drawings, in which—

Figure 1 is an elevation of our improved fire extinguisher;

Fig. 2 is a plan of the extinguisher;

Fig. 3 is a plan showing our improved means for holding and opening the duplex receptacle for the expelling substance.

Fig. 4 is a vertical, sectional elevation of the complete extinguisher;

Fig. 5 is an enlarged fragmental elevation partly in section illustrating our novel nozzle opening means; and

Fig. 6 is a sectional plan illustrating the bottle breaking means.

Referring by numerals to the accompanying drawings:

7 designates the body portion of the extinguisher which in the present instance is preferably constructed from a single piece of seamless tubing at the upper end of the body portion 7 and therewithin is an inter-

nally threaded ring 8 providing means for the attachment of a screw cap 9.

Formed on the upper face of the cap 9 is a pair of diametrically opposite integral ribs 10 which project free above the upper surface of said cap and afford a means for applying a spanner to assist in the placing or removal of the cap.

In one of the ribs there is formed a bore 11 which has at its outer end a threaded seat 12 arranged to receive a nozzle 13 and the inner end of the bore is threaded as at 14 to receive a plug 15 which plug, as clearly shown in Fig. 5, is hollow for a portion of its length and within the length of the hollowed out portion is provided with a reduced neck 16 whereby the plug may be readily broken for purposes hereinafter made clear.

The cap 9 is provided with a vertical and centrally disposed aperture surrounded by a threaded neck 17 arranged to receive a stuffing-box 18 through which is extended a stem 19 having at its upper end a knob 20 for its operation and at its lower end within the body 7 is an internally threaded holder in the form of an inverted cup 21.

Impinging between the knob 20 and the cap 9 and surrounding the stem 19 is a coil spring 22 arranged to normally hold the stem 19 elevated.

Carried by the stem 19 is a collar 23 which serves the double function of limiting the upward movement of the stem and also as a means to engage the plug 15 when it is desired to free the contents of the extinguisher.

Permanently secured to the body 7 of the extinguisher is a cup-shaped base 24.

At the upper end of the base 24 there is a shoulder 25 which forms a seat for a pair of crossed straps 26 in each of which at their intersecting points there is a threaded aperture arranged to receive the threaded end of a rod 27 the lowermost end of which extends through the bottom of the base and has secured thereto a handle 28 to facilitate the handling of the extinguisher.

29 designates leaves carried by the straps 26 preferably integral up-turned extensions of said straps.

30 designates pointed projections or cutters carried by said straps 26.

31 designates a can forming the outer

member of the watertight duplex receptacle hereinbefore referred to. This can is provided with a "thin tin" bottom 32 and with a reduced threaded neck 33 in the approximate center of which bottom there is formed a seat 34 to receive the stem 35 of a crow foot 35^a. By the word "can" we mean a receptacle made of any suitable material, and although in the present illustration of 10 our invention this "can" is shown and described as made of sheet-metal, yet we do not limit ourselves to that material, and wish it to be clearly understood that this receptacle 31 is to be made of any other material, whenever the circumstances indicate that the use of another material would be preferable to sheet-metal.

36 designates a bottle having a reduced neck 37 in which there is fitted a plate 38 arranged to support a seal 39. The can is secured in place by having its reduced neck threaded into the holder 21.

In the portion of the can not occupied by the bottle there is placed a quantity of bicarbonate of soda and in the bottle there is placed a quantity of sulfuric acid. It will thus be seen that both the bottle and the bicarbonate of soda are sealed within said watertight can.

30 In Fig. 4 the extinguisher is shown fully charged and in condition for use. The practical operation of the device is as follows:

The extinguisher is grasped by the handle 28 and inverted, the operator then strikes 35 the knob 20 upon the ground or floor which causes a movement of the stem 19 which movement presses the acid containing body against the crow foot, which breaks the bottle and drops the bicarbonate of soda 40 (which the bottle had previously held against the force of gravity) into the sulfuric acid; this movement of the stem 19 also moves the thin tin bottom of the can to engage with the cutters 30, thus forming 45 openings in the can for the discharge of the carbonic acid gas resulting from the combination of bicarbonate of soda and sulfuric acid.

When the extinguisher is in this inverted 50 position the fire extinguishing fluid is moved by gravity to a position uncovering the openings formed in the thin tin bottom. The movement of the stem 19 also causes the collar 23 to engage the end of the plug 55 15 and break it at its reduced neck portion, the dropping of the bicarbonate of soda into the sulfuric acid causing instantaneous pressure within the extinguisher body. The extinguisher is then ready for use and the 60 nozzle directed where desired.

By experiments we have found by dropping the bicarbonate of soda into the sulfuric acid a much larger volume of gas is instantly available for use than is obtained from extinguishers having the re-

verse construction, that is means for dropping the acid into the soda.

Another distinct advantage arising from our construction is means common to both operations of the extinguisher in freeing 70 the extinguishing fluid at the same time that the sulfuric acid and soda are combined to produce the expelling gas.

We claim:

1. In a fire-extinguisher, a container, a breakable sealed nozzle for said container, a yielding support within said container, a sealed watertight duplex receptacle within said container and connected to said support and having sealed within it separate 80 inert substances, means movable with said support for breaking the seal of said nozzle, means lying in the path of movement of said duplex receptacle for uniting said inert substances, and means lying in the path of said 85 receptacle for establishing communication between said receptacle and said container.

2. In a fire extinguisher, a container having a removable closure, a breakable sealed nozzle carried by said closure, a yieldingly 90 mounted stem operating through said closure arranged to engage said nozzle when moved, a receptacle for an expelling agency secured to and movable with said stem, and means in the path of movement of said receptacle for establishing a communication between said receptacle and said container when said stem is moved.

3. In a fire extinguisher, a support within said extinguisher, a hermetically 100 sealed can arranged for detachable connection with said support, an alkali and a bottle within said can, and a bottle breaking element within said can.

4. In combination with a fire extinguisher 105 arranged to contain a fire extinguishing substance and a support within said fire extinguisher, a device, designed for use as an expelling agent for said extinguishing substance, comprising a hermetically sealed 110 receptacle, means carried by said receptacle for detachable connection with said support, an alkali and a frangible element within said receptacle, and means in said receptacle for breaking said frangible element. 115

5. In a fire-extinguisher, a suitable tank or container, a cap threaded to one end of said container and having upon its upper surface two diametrically-opposite ribs, one of which is provided with a bore communicating with the interior of said tank during active use of the fire-extinguisher, a nozzle in said bore, and suitable means within said tank for ejecting a liquid through said bore and said nozzle. 120

6. As a new article of manufacture, a charging-can, for chemical fire extinguishers, comprising a sheet-metal can containing a bottle of acid and a quantity of dry substance which is separate from said acid 130

and adapted to be dropped into said acid when said bottle is broken, in combination with a bottle-breaking element also located within said charging-can, and screw threads 5 at one end of said can for detachably securing it to a support furnished therefor in a fire extinguisher.

9. A chemical fire apparatus comprising a tank, two non-communicating containers supported in said tank one above the other, a breakable closure for one of said containers, a breakable partition between said containers, and manipulative means for 10 breaking said closure and said partition whereby the contents of said containers are brought together to form a gas for the purpose of producing a pressure upon the liquid 15 contained in said tank.

In testimony whereof, we have signed our names to this specification, in presence of two subscribing witnesses.

EDWARD SCHAEFER.
OSCAR J. HOLMES.

E. L. WALLACE,
N. G. BUTLER.

- and adapted to be dropped into said acid when said bottle is broken, in combination with a bottle-breaking element also located within said charging-can, and screw threads 5 at one end of said can for detachably securing it to a support furnished therefor in a fire extinguisher.
7. A charging element for chemical fire extinguishers, comprising a quantity of 10 liquid and a quantity of dry substance, a separate container for each, the one container arranged to hold the one substance as well as the container for the other substance, means carried by the outer container 15 for detachably connecting it with a support furnished therefor in a fire extinguisher and means, within the outer container, for destroying the inner container when impacted.
8. A charging element for chemical fire 20 extinguishers, comprising a suitable receptacle, a quantity of dry substance in the said receptacle, a frangible bottle within the receptacle, a quantity of liquid within the bottle, means within the receptacle for
